United States Patent Office

Des. 197,508
Patented Feb. 18, 1964

197,508

METAL STUD

Fridtjof Berg, Warren, Ohio, assignor to Casings,
Incorporated, Milwaukee, Wis., a corporation of
Wisconsin

Filed June 11, 1963, Ser. No. 75,304

Term of patent 14 years

(Cl. D13—1)

Fig. 1.

Fig. 2.

FIGURE 1 is a front perspective view of a metal stud embodying my new design; and

FIGURE 2 is a cross sectional view taken on the plane of the line 2—2 in FIGURE 1.

I claim:

The ornamental design for a metal stud, as shown.
